UNITED STATES PATENT OFFICE.

MINER ROBINSON, OF NEWTON, MASSACHUSETTS.

OUTLET-BOX.

1,140,917.

Specification of Letters Patent. Patented May 25, 1915.

Application filed August 8, 1912. Serial No. 714,012.

To all whom it may concern:

Be it known that I, MINER ROBINSON, a citizen of the United States, residing at Newton, county of Middlesex, and State of 5 Massachusetts, have invented an Improvement in Outlet-Boxes, of which the following description, in connection with the accompanying drawing, is a specification, like characters on the drawing representing like

10 parts.

This invention relates to outlet boxes and particularly to those which are provided with a central opening to fit over the gas piping of a building which is piped for 15 gas. In the process of constructing a building which is both piped for gas and wired for electricity, it is customary for the gas fitters first to place the piping in the partially-completed building and to close by 20 removable caps the protruding ends of the gas piping wherever fixtures are to be applied. After the gas fitters are through with their work, the electrician comes onto the job and wires the building and places the 25 outlet boxes in position, these outlet boxes usually being inserted over the projecting ends of the gas pipes. It is a requirement of the underwriters that the outlet boxes which are used in connection with gas piping should 30 be electrically bonded on or connected to the gas piping. If the opening through the outlet box is only large enough to slip the gas piping, then the walls of said opening will engage the pipe and thus furnish the necessary bonding action, but with this construction 35 the outlet box can only be put in position over the gas pipe by first removing the cap from the projecting end thereof. It is, however, contrary to the requirements of the 40 gas authorities in some localities to permit electricians or persons other than licensed gas fitters from removing this cap, and it is, therefore, very desirable to provide an outlet box which can be put in place over 45 the end of the gas pipe without moving the cap and which when in place can be bonded to the gas pipe so as to meet the requirements of the underwriters.

My invention aims to provide an outlet 50 box and the like having a novel bonding element which is adapted to engage the pipe with a wedging action, and further to provide an outlet box having a construction which permits it to be set into place over 55 the capped end of the gas pipe without re-

moving the cap and in which the bonding element acts not only to bond the box to the pipe but also to seal the space around the pipe, all as will hereinafter more fully be described and claimed.

In order to disclose the principle of my invention I have illustrated in the drawing a selected embodiment thereof, but I wish it understood that the invention is not limited to the constructional details shown.

In the drawings, Figure 1 is a face view of an outlet box embodying my invention showing it clamped to the pipe; Fig. 2 is a rear view thereof; Fig. 3 is a section on the line *x-x*, Fig. 1; Fig. 4 is a similar view 70 showing the clamping member in inoperative position and showing the box in the condition in which it is received by the electrician ready to be placed over the gas pipe; Fig. 5 is a section on the line *a-a*, Figs. 2 75 and 3; Fig. 6 is a section on the line *b-b*, Figs. 1 and 7; Fig. 7 is a perspective view of a portion of the outlet box showing the pipe-receiving aperture therethrough and the seat for the clamping member; Fig. 8 is 80 an underside perspective view of the clamping member; Fig. 9 is a plan view of the outlet box showing the condition in which it is shipped.

3 designates an outlet box which may 85 have any suitable or usual construction with the exception of the pipe-receiving aperture and the clamping means for clamping the box to the gas pipe, and 4 designates a projecting end of gas piping over which the 90 outlet box is inserted, said piping being closed by the usual cap 5. If desired the outlet box 3 may be secured to the backing board 6 by means of screws 7 in usual manner. The outlet box is provided with conduit-receiving openings 8 through which the 95 conduit leads into the box. As stated above, the gas pipe 4 is sealed with its cap 5 by the gas fitter at a time during the building operations prior to that at which the electrician puts the outlet box in place and wires up the building, and the requirements in some localities are that the outlet box 100 shall be of such a nature that it may be put in place and bonded to the pipe to make a good ground connection therewith without removing the cap 5 from the pipe. It is also a requirement in some localities that the open space around the pipe shall be closed or sealed. To meet these requirements I 110

make the outlet box 3 with a pipe-receiving aperture 9 which is large enough to receive the cap 5 freely and which is preferably formed eccentrically of the outlet box, as seen in Fig. 2. When the aperture 9 is thus situated eccentrically one wall 10 thereof will preferably be situated at a distance from the center of the box substantially equal to the radius of the pipe 4, so that when the pipe is clamped against the wall 10 the pipe and outlet box will be situated concentrically of each other. This construction permits the outlet box to be placed over the capped end of the pipe 4, and then to be brought into position concentrically of the pipe. The outlet box is bonded to the pipe by means of a bonding member 12 which can be moved toward and from the opening 9 preferably in a radial direction and which is provided with means whereby when it is in bonding position it will be clamped against the pipe 4 with a wedging action. As herein shown this bonding member 12 is provided with a concave pipe-engaging face 13, and with lips 14 at opposite edges which rest on the flange 15 that surrounds the opening 9. Said bonding member is also provided with a tongue 16 which is adapted to slide pack and forth in a slot 17 formed in the outlet box, said tongue and slot operating to guide the bonding member in its movement toward and from the pipe. The outlet box is also provided with the projections 18 which are provided with the inclined faces 19, said projections constituting a rest for the bonding member when it is in its inoperative position and the inclined faces 19 thereof co-operating with the bonding member to secure the wedging action of the latter against the pipe, all as will be further hereinafter described.

The outlet box is also provided with the inclined faces 20 which co-operate with wedging faces on the bonding member to assist in securing this wedging action. The bonding member is made thicker at its inner end, as shown at 21, and one side of this thicker portion 21 forms the pipe-engaging face 13, while the opposite side is provided with the inclined faces 22 which co-operate with the inclined faces 20 on the outlet box. The rear edge 23 of the thinner portion of the bonding member co-operates with the inclined faces 19 and is preferably inclined. When the bonding member is withdrawn into its inoperative position, the thickened portion 21 rests on the surfaces 24 of the outlet box at either side of the slot 17, and the thinner or tail end of the bonding member rests on the projections 18, as seen in Fig. 4. The bonding member is provided with an aperture 25 to receive a clamping bolt 26 which is preferably in the nature of an ordinary stove bolt. This screw 26 car-

ries a nut 27 which is confined in an elongated recess or groove 28 formed in the back side of the outlet box, the walls 29 of said groove preventing the nut from turning. The head of the clamping screw 26 is provided with a screw-driver slot so that the clamping member may be tightened or loosened from the front by the use of a screw-driver. The bonding member is also provided with a projection 30 which is adapted to enter a notch 31 formed in the flange of the outlet box when said bonding member is in inoperative position and which fits between the projections 18 when the bonding member is in operative position.

When the parts of the outlet box are being assembled for shipment the bonding member is put in place and slipped into its operative or outward position, as shown in Figs. 4 and 9, with the underside of the thickened portion 21 resting on the surfaces 24, and the rear of the bonding member resting on the projections 18 and with the projection 30 occupying the slot 31. The clamping screw 26 is tightened so as to hold the parts firmly in position. This is the way the outlet box is received by the electrician, and in placing it in position he merely inserts it over the capped end 5 of the pipe and then shifts it so as to bring the pipe against the wall 10. Thereafter he merely loosens the clamping screw 26 by means of a screw-driver and then moves the bonding member radially into engagement with the pipe. When the bonding member is thus in engagement with the pipe the inclined surfaces 22 of said member engage the inclined surfaces 20 of the outlet box and the inclined surface 23 engages the inclined surface 19. As a result when the clamping screw 26 is tightened the bonding member tends to slide down the inclined surfaces 20 and 19, thus forcing the clamping member hard against the pipe 4. The bonding member 12 is thus also in the nature of a clamping member in that it is clamped firmly against the pipe. This member, therefore, might be designated as a combined bonding and clamping member.

Since the bonding member 12 has a construction which permits it to be firmly clamped against the pipe it would be possible to support the outlet box in position without attaching it to the back-board 6, for if the pipe 4 is firmly sustained the outlet box will be rigidly held in position by the clamping or wedging action of the combined clamping and bonding member 12.

The two parallel clamping surfaces 22, 23 on the bonding member and the co-operative parallel clamping surfaces 20, 19 on the outlet box co-operate to hold the bonding member in proper position. It will be noted that the surfaces 19, 23 are at a greater radial distance from the center than

the surfaces 20, 22, and by means of this construction the bonding member is held in parallel relation and is prevented from tipping up on one end or the other while it is being clamped in position. I also desire to call attention to the fact that the combined clamping and bonding member 12 has such a construction that it seals or closes the opening around the pipe 4 when it is in 5 clamping position, as shown in Fig. 1. This member is, therefore, a sealing member for the aperture 9 as well as a bonding member.

One function of the projection 30 is to close the rear end of the slot 17 when the member 12 is in its clamping position. Referring to Fig. 1 wherein the slot 17 is shown in dotted lines, it will be seen that the outer end thereof extends beyond the face 23, but this extending end is sealed or 10 closed by the projection 30.

While I have illustrated herein the preferred embodiment of my invention, I do not wish to be limited to the constructional features shown or in any way except as by 15 the appended claims.

Having fully described my invention, what I claim as new and desire to secure by Letters Patent is:—

1. An outlet box and the like having an 20 eccentrically-located pipe-receiving aperture which is normally of a size to permit the capped end of a pipe to be passed therethrough, and one side of which is situated so that when said pipe is resting there- 25 against said pipe will be concentric relative to said box, and a clamping and bonding member slidably sustained by the outlet box for movement toward and from said aperture and having a shape substantially to close 30 the portion of the aperture not occupied by the pipe.

2. An outlet box and the like having a 35 pipe-receiving aperture which is normally of a size to permit the capped end of a pipe to be passed therethrough, and a bonding member slidably sustained by said outlet box for movement toward and from the aperture and having a shape substantially to close or seal when in bonding position the 40 portion of said aperture not occupied by the pipe.

3. An outlet box and the like having a 45 pipe-receiving aperture which is normally of sufficient size to permit the capped end of a pipe to be passed therethrough, and a one-piece bonding member shaped substantially to close when in bonding position the portion of the aperture not occupied by the pipe.

4. In an outlet box and the like having a 50 pipe-receiving aperture and two separate wedging surfaces situated at different distances from said aperture, of a bonding member adapted to engage said surfaces and 55 be clamped thereby against the pipe.

5. The combination with an outlet box 60 having a pipe-receiving aperture and two wedging surfaces situated at different distances from said aperture, of a bonding member to engage said surfaces, a pipe inserted through the aperture, and means situated between said surfaces to force the bonding member against the wedging surfaces, thereby to clamp it against the pipe. 70

6. The combination with an outlet box 75 having a pipe-receiving aperture of a size sufficient to receive the capped end of a pipe and also having two wedging surfaces situated at different radial distances from said aperture, of a bonding member to engage 80 said surfaces, and a clamping bolt located between said wedging surfaces to force the bonding member against the surfaces thereby to clamp it against the pipe with a wedging action. 85

7. The combination with a pipe, of an outlet box having a pipe-receiving aperture through which said pipe passes and which is sufficiently larger than said pipe to receive the capped end thereof, and a combined 90 clamping and sealing member to engage the pipe and substantially seal the portion of the aperture not occupied by the pipe. 90

8. The combination with a pipe, of an outlet box having a pipe-receiving aperture 95 through which said pipe passes and which is sufficiently larger than said pipe to receive the capped end thereof, and a combined 100 clamping and sealing member adapted to clamp the pipe against one side of said aperture and substantially to seal the portion of the aperture not occupied by the pipe.

9. The combination with a pipe, of an outlet box having a pipe-receiving aperture through which said pipe passes and which is sufficiently larger than said pipe to receive the capped end thereof, and a one-piece combined 105 clamping and sealing member adapted to clamp the pipe against one side of the aperture and substantially seal the portion 110 of the aperture not occupied by the pipe.

10. The combination with an outlet box having an eccentrically-arranged aperture which is normally of a size to receive the capped end of the pipe, one wall of the aperture being situated so that when the pipe is placed thereagainst said pipe will have a concentric relation to the box and an eccentric relation to the aperture, of a clamping member to clamp said pipe against said wall 115 120 of the aperture.

11. The combination with an outlet box having an eccentrically-arranged aperture which is normally of a size to receive the end of the pipe, one wall of the aperture 125 being situated so that when the pipe is placed thereagainst said pipe will have a concentric relation to the box and an eccentric relation to the aperture, of a clamping member to clamp said pipe against said wall 130

- of the aperture, said clamping member being of a size and shape to seal the space around the pipe.
12. The combination with an outlet box 5 having a pipe-receiving aperture, of a clamping member slidable toward and from the aperture and means for clamping said member against the pipe, said box and clamping member having cooperating means separate 10 from the clamping means to guide the member in its sliding movement.
13. The combination with an outlet box having a pipe-receiving aperture and a slot 15 extending radially therefrom, of a clamping member slidable longitudinally of the slot and having a laterally-extending finger to enter the slot.
14. The combination with an outlet box having a pipe-receiving aperture and a ra- 20 dially-extending slot, of a clamping member slidable longitudinally of the slot and having a laterally-extending finger to enter said slot, and a clamping bolt extending through the clamping member and slot.
- 25 15. The combination with an outlet box having a pipe-receiving aperture and a plu- rality of wedging surfaces situated at differ- 30 ent radial distances from the aperture, of a clamping member adapted to engage said surfaces and maintained in parallel relation thereby.
16. The combination with an outlet box having a pipe-receiving aperture and a wedging surface, of a bonding member
- adapted to engage said surface and having 35 a laterally-extending finger at its pipe-engaging end, and means to force the bonding member against said wedging surface there- by to clamp it against said pipe, said finger providing an extended pipe-engaging sur- 40 face.
17. The combination with an outlet box having a pipe-receiving aperture and a wedging surface, of a bonding member adapted to engage said surface and having a 45 laterally-extending finger at its pipe-engaging end, which finger extends through the aperture, and means to force the bonding member against the wedging surface thereby to clamp said finger against the pipe. 50
18. The combination with a pipe, of an outlet box having a pipe-receiving aperture into which said pipe passes and which is sufficiently larger than said pipe to receive the capped end thereof, and a bonding mem- 55 ber slidably sustained by said outlet box for movement toward and from the aperture and having a shape substantially to close the portion of said aperture not occupied by the pipe.

In testimony whereof, I have signed my name to this specification, in the presence of two subscribing witnesses.

MINER ROBINSON.
